United States Patent

Des. 241,277
Patented Aug. 31, 1976

241,277

BLOOD CELL SCANNING DEVICE CONSOLE OR SIMILAR ARTICLE

James A. Odom, Jr., Apple Valley, and Norbert Thomas Wolfe, Minnetonka, Minn., assignors to Honeywell, Inc., Minneapolis, Minn.

Filed Mar. 5, 1975, Ser. No. 555,508

Term of patent 14 years

Int. Cl. D24—01

U.S. Cl. D83—1 F

FIG. 1

FIG. 2

FIG. 1 is a top front perspective of a blood cell scanning device console or similar article showing our new design, the console being broken away for convenience of illustration; and

FIG. 2 is a right side elevation thereof.

The undisclosed rear and bottom panel are substantially plain and unornamented.

We claim:

The ornamental design for a blood cell scanning device console or similar article, substantially as shown and described.
